UNITED STATES PATENT OFFICE.

ANDREW WICKEY, OF QUINCY, ILLINOIS.

BALING-PRESS.

SPECIFICATION forming part of Letters Patent No. 366,547, dated July 12, 1887.

Application filed July 21, 1886. Serial No. 208,721. (No model.)

To all whom it may concern:

Be it known that I, ANDREW WICKEY, of Quincy, in the county of Adams and State of Illinois, have invented certain Improvements 5 in Baling-Presses, of which the following is a specification.

At the present day there is in general use a class of so-called "continual" baling-presses, in which the loose hay or other material is received through a top opening into what is called a "feed-chamber," from which it is driven by a reciprocating plunger in a continuous body through a trunk or tunnel in which its compression is effected, and from which it is delivered at the opposite end, the body being divided in the course of its formation into lengths or sections suitable for bales by boards introduced at proper intervals.

The aim of my invention is to permit the 20 more convenient introduction of the charge and to secure a more effective compression of the hay; and to this end it consists in providing the receiving end of the trunk, sometimes termed the "feed-chamber," with inwardly and 25 outwardly movable side walls combined with operating mechanism by which they are caused to move outward during the introduction of the successive charges of loose hay, in order to afford an increased space for their admission, 30 and then urged inward previous to or during the advance of the plunger.

My invention is susceptible of embodiment in various forms which will be apparent to the skilled mechanic after an examination of 35 the accompanying drawings and the following description; but I have represented in the drawings a particular construction which appears to be the most serviceable under ordinary conditions. Inasmuch as the press may 40 be in other respects of ordinary construction, I have illustrated in the accompanying drawings only those portions which are directly associated with my invention.

In the accompanying drawings, Figure 1 45 represents a vertical cross-section through the receiving end or feed-chamber of the press on the line $x-x$ of Fig. 2. Fig. 2 is a longitudinal horizontal section on the line $y-y$ of Fig. 1. Fig. 3 is a longitudinal vertical section on the 50 line $z-z$ of the preceding figure.

Referring to the drawings, A represents the frame of the press, which may be of any ordinary or appropriate construction; B, the receiving end of the horizontal trunk or chamber, commonly known as the feed-chamber; 55 B', the pressure-chamber or trunk, open at both ends, into and through which the material is delivered by the plunger from the feed-chamber; C, the feed-opening, through which the hay is introduced into the top of the chamber; 60 and D, the horizontal reciprocating plunger or beater, which advances periodically beneath and beyond the feed-opening for the purpose of adding the successive charges to the mass of hay and of gradually advancing the mass 65 through the delivery end of the trunk in the ordinary manner. Ordinarily the side walls a of the receiving-chamber B are stationary. Under my improved construction they are 70 movable, so that they may be separated horizontally, to afford an increased space between them for the admission of the hay, and then moved inward in line with the walls of the pressure-chamber, so that the material may be delivered between them by the plunger 75 into the pressure-chamber or trunk beyond. It will be perceived that the movement of the walls inward to positions flush with the walls of the pressure-chamber is necessary in order to permit the delivery of the charge. If the 80 feed-chamber were permitted to remain of greater width than the pressure chamber or trunk, the charge projecting laterally beyond the mouth of the feed-chamber would lodge firmly against its end. At its upper end each 85 of these walls is connected by links b to arms c on a horizontal rock-shaft, d, mounted in fixed bearings e on the outside of the main frame. At its lower edge each of the walls is connected to two toggle links or joints, f, which are 90 connected by upright rods or bars g to the arms of the rock-shaft above. These bars g are connected by links h to crank-arms i, fixed on opposite sides of a horizontal shaft, j, lying athwart the main frame and mounted in bearings 95 secured to its under side. Centrally upon this shaft there is fixed an arm, k, the upper end of which stands normally in the path of the plunger D, while its lower end is pivoted to a sliding rod, l, encircled by a spiral spring, m, 100

which tends to urge the arm in the direction indicated by the arrow.

When the plunger is retracted to permit the introduction of a charge of hay, it releases the 5 arm *k*, whereupon the spring *m* acts to turn the rock-shaft in such manner that its arms *i* effect the deflection of the toggle-joints *f* and the rotation of the rock-shaft *b*, and the consequent retraction or separation of the walls *a*. 10 When, however, the plunger advances, it encounters the arm *k*, and, turning the same, acts through the intermediate parts to force the walls *a* inward to their operative positions, thus compressing the hay laterally between them previous to the advance of the plunger. Thus it 15 is that the receiving-chamber is expanded laterally for the reception of each charge, and then reduced or contracted automatically as the plunger advances to carry the charge forward.

The essence of the invention resides in the movability of the walls of the feed-chamber in a press of the class now under consideration, requiring the delivery of the charge from the 20 feed-chamber into the trunk or chamber beyond, and the combination of automatic operating mechanism therewith; and it will be manifest to the skilled mechanic that this operating mechanism may be variously constructed and 25 that it may be actuated either by the plunger, as shown, or in any other appropriate manner.

While the best results are attained by arranging both walls of the receiving-chamber to retreat, as described, it will of course be understood that either wall may be left stationary, as usual.

I am aware that a cotton-press having a vertical chamber to receive the cotton and a screw - driven plunger which enters the receiving end of the chamber to compress the 40 cotton therein has been provided with automatic means for moving one of the side walls inward during the advance of the plunger, in order to effect the compression of the bale both 45 laterally and longitudinally, and I do not therefore claim, broadly, a compressing-chamber having side walls movable inward and outward.

My invention has reference to a class of 50 presses operating in a manner widely different from the cotton-press above referred to. In my press the movable walls are applied, not to the compressing-chamber, but to a feed-chamber open at its side and from which the plunger 55 is never wholly withdrawn. My feed-chamber with its movable walls is combined with a distinct compressing-chamber or trunk, and the sole purpose of the movable walls is to reduce the feed chamber containing the loose 60 hay to a size corresponding to that of the

pressure-chamber beyond, so that the hay may be delivered from the first chamber to the second.

Having thus described my invention, what I claim is—

1. In a continuous baling-press of the type herein described, the combination of an open-ended trunk or chamber in which the compression of the hay is effected, a preceding feed-chamber provided with a top opening for 70 the admission of the hay, and with side walls movable inward and outward, a plunger traversing the feed-chamber past the feed-opening to advance the successive charges and add them to the accumulated body in the 75 pressure-chamber, and mechanism, substantially as described, acting to move the walls of the feed-chamber outward beyond the walls of the pressure-chamber during the retreat of the plunger, and to move them inward in line 80 with the walls of the pressure-chamber during the advance of the plunger, whereby the feed-chamber is enlarged to receive the charge of loose material, and then reduced to a size corresponding with the pressure-chamber, in 85 order that the charge may be delivered to the latter.

2. In a continuous baling-press, the combination of the trunk or pressure-chamber open at its ends, the feed-chamber *B*, having movable side walls, *a*, and a top opening, *C*, a reciprocating plunger, *D*, arranged to traverse the feed-chamber, the lever *k*, mounted in the path of and actuated by the plunger, and the toggle-joints and their connections between 95 the lever *k* and the movable walls *a*, substantially as described, whereby the advancing plunger is caused to force the two walls inward flush with the walls of the pressure-chamber.

3. In a continual baling-press, the combination of the pressure-chamber or trunk open at its ends, the receiving-chamber *B*, provided with a top opening and with the inwardly-movable side walls, *a*, the rock-shafts applied to the frame, the toggle-joints connecting said shafts with the movable walls *a*, the transverse rock-shaft *j*, provided with crank-arms connected to the toggle mechanism, the lever *k*, mounted in the path of the plunger, and the spring *m*, acting upon the lever, said parts constructed and arranged for joint operation, substantially as described.

In testimony whereof I hereunto set my hand, this 17th day of June, 1886, in the presence of two attesting witnesses.

ANDREW WICKEY.
